VARIABLE CAPACITY PUMP

Walter R. Eames, Jr., Royal Oak, Mich., assignor to Eaton Manufacturing Company, Cleveland, Ohio, a corporation of Ohio

Filed Aug. 13, 1956, Ser. No. 603,581

5 Claims. (Cl. 103—11)

In many applications requiring pressurized hydraulic fluid to perform work in a hydraulic circuit, the volume requirements vary greatly. To satisfy the demand in such a system, a variable capacity pump is ordinarily used. This results in a pump which, by necessity, is more complicated than a constant displacement type pump.

This invention relates to the accomplishment of the function of a variable displacement type pump by using a constant displacement pump with a novel valving arrangement.

An object of this invention is to provide a constant displacement pump with a novel valving arrangement to replace a variable displacement pump.

A further object is to provide a pump having multiple pumping strokes per pump cycle.

These and other objects and advantages will become more apparent from the following detailed description of the device and from the accompanying drawings.

FIGURE 1 schematically illustrates a pump and novel control therefor.

FIGURE 2 shows the control illustrated in FIGURE 1 in a different operating position.

FIGURE 3 is a modification of the control system.

FIGURE 4 illustrates the modification shown in FIGURE 3 in a different operating position.

This device is comprised of a fluid control system comprising a single pump having at least two pumping chambers of equal or unequal capacity, depending upon the particular application of the structure or of a plurality of pumps having single or multiple pumping chambers with equal or unequal capacity, depending upon the application of the structure. For convenience, the device will be described utilizing a single pump with two pumping chambers of unequal capacity. The pumping chambers are in communication with a fluid reservoir which provides the necessary supply of oil to the pump. In a structure utilizing two pumping chambers, the communication between the reservoir and one of the chambers is provided with a check valve which allows flow to the chamber from the reservoir but prevents reverse flow and this first chamber is also provided with a discharge communication to an output line. The second pumping chamber is provided with similar communicating lines to the reservoir and the output line except that there is no check valve provided in the intake line for the second chamber. A valve means is provided having a plunger which is connected to the discharge from both chambers in the output line, tending to move the valve in one direction, and spring means opposing this fluid force. When the valve plunger is longitudinally moved a certain amount in response to fluid pressure, the output from both of said pump chambers is communicated by a first bypass line means to the intake of the first mentioned pump chamber. When the valve plunger is moved further in the same direction, the combined output of the pump is communicated to the intake of both of said pump chambers by said first bypass line and a second bypass line connected to said valve and said second mentioned pump chamber. The bypass return flow in the first mentioned line is prevented from returning to the reservoir by the previously mentioned check valve. Therefore, when the valve is moved so that the first bypass line and at least a portion of the second bypass line are in communication with the combined output of the

2

pump, a volume equal to the output of the first chamber is merely shunted back to the first chamber with no resulting loss of work except for frictional line losses. When the pump output is decreased or the output requirement is increased, the valve is closed in response to the differential of the spring force and reduced discharge pressure and the full capacity of the pump is discharged to the output line. If for any reason the output requirement is greatly diminished or the pump output is greatly increased, the pressure in the output line increases and the valve is completely opened which results in a bypass of the full capacity of the pump back to the pumping chambers. A communication is provided between the work performing device and the reservoir to provide a return for the fluid.

5 It is to be noted that a pump having more than two pumping chambers can be utilized. If, for example, a unit having four pumping chambers is used and it is desired to be able to motor one, two, or three of the chambers, check valves are placed in the communicating lines between the reservoir and the intake means to each of the chambers to be motored to prevent flow of fluid back to the reservoir.

10 Referring to the drawing for a more detailed description of the invention, the fluid device 10 is provided with a rotary pump 12 having a rotor 14 and a housing 16. A rotary pump is illustrated but the invention is not limited to this type pumping structure. A pressure relief valve 18 communicates with the discharge and intake of the pump 12 in a manner which will be described in detail in the following description.

15 The pump 12 is provided with a relatively large capacity chamber 20 and a smaller capacity chamber 22. A reservoir 24 furnishes fluid to the high capacity pump chamber by means of fluid conduits 26, 28, and 30. A check valve 32 is interposed in conduit 28 which allows flow from the large capacity chamber to the reservoir and the small capacity chamber is furnished with fluid from the reservoir by means of fluid conduits 26, 34, and 36. The valve 18 is provided with a pair of bypass ports, 38 and 40, the port 38 communicating with the conduit 36 by means of a conduit 42 and bypass port 40 communicating with conduit 30 by means of conduit 44.

20 A conduit 46 is connected at one end to the discharge side of the low capacity chamber 22 and is connected at the other end to chamber 48 of valve 18. A conduit 50 is connected at one end to the discharge of the high capacity chamber 20 and at the other end to the conduit 46 so that the discharge from both the large capacity and the small capacity chambers is communicated to the valve chamber 48. The remainder of the valve structure 18 is comprised of a piston 52 having an end portion in communication with the chamber 48 and a compression spring 54 acting against the piston 52 and reacting against an adjustable plug 56. An output port 58 is connected to the chamber 48 of valve 18 and provides a communication between the control system 10 and the working system (not shown). Obviously, the output port can be located at any point in the discharge conduit 46 and is shown formed in the valve housing merely for a convenience and is not limited to the exact location shown in the drawing. Also, there is a communication between the exhaust side of the working system and the reservoir to provide a return means for fluid to the reservoir. The operation of this device is described in the following manner.

25 When the pump rotor 14 is rotated in a counterclockwise direction, fluid from the sump is communicated both to the large capacity chamber and the small capacity chamber. Fluid under pressure is then discharged into the conduits 46 and 50 which jointly communicate with the valve chamber 48 and thence to the output port 58.

When the discharge requirements to the working system are such that the full output pressure of the pump is required, the piston 52 of control valve 18 will remain in the position shown in FIGURE 1. At this time, the total pressure of the low capacity and high capacity chamber is directly communicated to the output port 58 with no bypass of pressure from either of the working chambers back to the pump. When the discharge requirements are decreased or there is a substantial increase in pump flow, a pressure rise in the discharge line and in the chamber 48 results in the movement of piston 52 of valve 18 to a position wherein the bypass port 40 is uncovered. The combined pump discharge is now in communication with both the output conduit 58 and the bypass conduit 44 which bypasses a portion of the output of the combined pump discharge back to the large capacity chamber. At this time, there is no motoring effect but when the requirements are again reduced until piston 52 moves to a position establishing at least a partial communication between output conduit 58 and bypass conduit 42, the discharge from the large capacity chamber is bypassed or recirculated back to the large capacity chamber resulting in a motoring of the large capacity chamber. Under this operating condition, the high capacity chamber is in a motoring condition, but most important, this motoring does not result in any power loss except for line losses, since the discharge from the large capacity chamber is communicated back to the intake side of the large capacity chamber. If the discharge requirement falls below a predetermined minimum, the piston 52 moves further upward, as shown in FIGURE 2, resulting in greater communication of the bypass port 38 with the chamber 48. Consequently, the total discharge of the high capacity chamber and a portion of the discharge of the low capacity chamber, less line losses, is bypassed back to the intake of both chambers of the pump with the high capacity chamber being motored and the remaining portion of the low capacity chamber output, less line losses, being returned to the low capacity chamber input and the reservoir.

FIGURE 3 illustrates a modification of the control valve. A valve 118 is provided with a valve body 155, a piston 152, a compression spring 154 interposed between the piston 152 and the adjustable plug 156 and a pair of bypass ports 138 and 140 communicating by conduit means with the low and high capacity chambers, respectively. An orifice 160 is provided in the piston 152 so that fluid flow from the discharge side of the large capacity chamber and the small capacity chamber flows through the orifice into the discharge conduit 158. This modified structure operates in the following manner.

When the pump rotor is rotated, fluid from the reservoir 124 is communicated to both the large capacity chamber 120 and the small capacity chamber 122. Fluid under pressure is then discharged into the discharge conduits 146 and 150 which communicate with the valve chamber 148, orifice 160, and the discharge conduit 158.

When the flow requirements to the system are such that the discharge of the pump does not exceed those requirements, piston 152 of the control valve 118 will remain in the position shown in FIGURE 3. At this time, the combined flow of the small capacity chamber and the large capacity chamber is directly communicated to the output conduit 158 and there is a maximum permissible pressure drop across orifice 160 with no bypass of fluid from either of the working chambers back to the pump. When the discharge of the pump is increased above the requirements of the working system or the requirements of the working system are reduced, flow across the orifice is increased and there is a consequent increase in pressure drop across the orifice which results in a movement of the valve to a position in which bypass port 140 is uncovered. The combined pump discharge is now in communication with both the output conduit 58 and the bypass port 140 which results in a bypass of

5 a portion of the output of the combined pump discharge back to the large capacity chamber. At this time, there is no motoring but when the flow requirements are again reduced until piston 152 moves to a position establishing at least a partial communication between output conduit 158 and bypass conduit 142, the discharge from the large capacity chamber is bypassed or recirculated back to the large capacity chamber with no resulting loss of work except for frictional line losses. Under this condition, the large capacity chamber is motoring. It is obvious therefore, that this modification of the device is responsive to flow rather than being pressure responsive. If the discharge of the pump increases further, piston 152 of valve 118 moves further upwardly (as viewed in FIGURE 4) resulting in greater communication of bypass port 138 with the output conduit. Consequently, an increased quantity of flow from the pump is bypassed to the intake of the low capacity chamber of the pump.

20 It is obvious that the ratio of the capacity of the large capacity chamber and the small capacity chamber can be varied to obtain any percentage of reduction in flow that is desired. For example, in use in a transmission, a small basic flow is required for leakage and a much higher flow is necessary when effecting the movement of 25 one or more clutches. In such an application, the structure disclosed herein would shift into high range to fill the clutch rapidly and then drop to low range to merely hold the pressure.

20 Also, as previously mentioned, more than two pumping chambers can be utilized and a device having two chambers has been illustrated merely for purposes of clarity and simplicity.

35 The structure disclosed herein describes a fluid control system comprising a pump having at least two pumping chambers or a structure having a plurality of pumps with each pump having single or multiple pumping chambers wherein control means is provided to allow selective communication of the combined discharge of said pump or pumps with the inlet of one or more of said pumping chambers.

40 This control can be either pressure responsive or flow responsive, depending upon the particular application which is required.

45 While the present invention has been described in connection with certain specific embodiments, it is to be understood that the foregoing description is merely exemplary and that the concept of this invention is susceptible of numerous other modifications, variations, and applications which will be apparent to persons skilled in the art. The invention is to be limited, therefore, only 50 by the broad scope of the appended claims.

I claim:

1. A fluid control system comprising means having a plurality of fluid pumping chambers, a single pressure responsive valve, a work communicating means, each of said pumping chambers being provided with an intake means and a discharge means, said intake means being in fluid communication with said valve and said discharge means being in fluid communication with said valve and said work communicating means, means in said valve being movable in response to the combined pressure of the fluid discharge of said pumping chambers and being movable to a position to allow fluid communication between said discharge means and one or more of said intake means, one-way valve means interposed between said one or more intake means and the remaining of said intake means preventing fluid flow from said one or more of said intake means to the remaining of said intake means, whereby at least a portion of said fluid discharge from said pumping chambers is bypassed to said one or more of said intake means.

2. A pumping device comprising a pump having a low capacity pumping chamber and a high capacity pumping chamber, each of said pumping chambers having an intake means and a discharge means, a fluid reservoir in fluid communication with said intake means of said pump-

ing chambers, check valve means interposed between at least one of said intake means of said pumping chambers and the remaining intake means of the remaining pumping chambers to prevent flow of fluid from said one intake means to said remaining intake means, a single control valve, said intake and said discharge means of said pumping chambers being in fluid communication with said control valve, means in said control valve to allow fluid communication between said discharge means and said one intake means, and a work outlet chamber in fluid communication with said discharge means of said pumping chambers.

3. A fluid pump means comprising a multiplicity of pumping chambers, each of said pumping chambers having an intake means and a discharge means, a single control valve, said intake means and said discharge means communicating with said valve, a work outlet means in fluid communication with said discharge means, flow responsive means in said valve to selectively prevent fluid communication between said intake means and said discharge means and to allow selective fluid communication between one or more of said intake means and said discharge means upon a sufficient increase in fluid flow in said valve, and one-way valve means interposed between said one or more intake means and the remaining of said intake means preventing fluid flow from said one or more of said intake means to the remaining of said intake means.

4. A fluid control system comprising means having a plurality of pumping chambers, each of said pumping chambers having an inlet means and a discharge means, reservoir means in fluid communication with said inlet means, one-way valve means interposed between said one or more inlet means and the remaining of said inlet means

to prevent flow from said one or more of said inlet means to the remaining of said inlet means and to said reservoir, a single control valve in fluid communication with said discharge means and pressure responsive means in said

5 valve to selectively communicate said discharge means with one or more of said inlet means.

5. A fluid control system comprising means having a plurality of pumping chambers, each of said pumping chambers having an inlet means and a discharge means, 10 reservoir means in fluid communication with said inlet means, one-way valve means interposed between said one or more inlet means and the remaining of said inlet means to prevent flow from said one or more of said inlet means to the remaining of said inlet means and to said reservoir, 15 a single control valve in fluid communication with said discharge means and flow responsive means in said valve to selectively communicate said discharge means with one or more of said inlet means.
